UNITED STATES PATENT OFFICE.

GILBERT PARK, OF WALES, AND JOHN E. GODDARD, OF SPENCER, ASSIGNORS
OF ONE-HALF TO JOHN G. AVERY, OF SPENCER, MASSACHUSETTS.

WEFT STOP-MOTION FOR LOOMS.

SPECIFICATION forming part of Letters Patent No. 463,372, dated November 17, 1891.

Application filed January 12, 1891. Serial No. 377,516. (No model.)

To all whom it may concern:

Be it known that we, GILBERT PARK and JOHN E. GODDARD, citizens of the United States, and residents, respectively, of Wales and of Spencer, in the State of Massachusetts, have jointly invented a new and useful Improvement in Weft Stop-Motions for Looms, of which the following is a specification.

This invention relates to mechanical devices for automatically stopping the loom when the thread of the weft or filling breaks or a bobbin becomes exhausted or fails for any reason to pass through the shed of the warp when the loom is running; and the invention consists in certain novel combinations of parts hereinafter set forth and claimed.

The distinctive objects of the present invention are, first, to lift and lower the feelers by a peculiarly simple and novel device; secondly, to actuate the lifter by a self-adjusting one-part spring-finger; thirdly, to provide for automatically and immediately readjusting the feeler-lifter in case the weaver in moving the lay by hand should fail to readjust it before starting the loom; fourthly, to provide strong and simple mechanical transmitting devices for actuating the belt-shipper or its equivalent when the filling is absent, so that the loom shall stop before the reed strikes the fell of the cloth, whereby we avoid turning the loom back by hand before starting up. With our device it is only necessary to push the lay back, when it is ready for the shuttle without the loss of a pick.

Two sheets of drawings accompany this specification as part thereof.

Figure 1 of the drawings represents a top view of central fragments of the breast-beam and the retracted lay of a loom provided with our stop-motion. Fig. 2 represents a sectional elevation of the parts shown in Fig. 1, illustrating the advance of the lay, with the filling absent, by dotted outlines of some of the parts in a second position of the lay. Fig. 3 represents a sectional elevation with the plane of section at 3 3, Fig. 1, and with the lay in its most advanced position, illustrating also in dotted lines the automatic readjustment of the feeler-lifter. Fig. 4 represents a fragment-

ary reverse view of the attachments to the lay, showing their other side as compared with Fig. 3. Fig. 5 is a fragmentary view looking forward from the lay, showing the attachments to the breast-beam. Fig. 6 is a front view of the attachments to the lay, and Fig. 7 is a perspective view of the feeler-lifter detached.

Like letters of reference indicate corresponding parts in the several figures.

We have shown and will describe our stop-motion as applied to a loom having a "Knowles" belt-shipper, as set forth in Patent No. 197,641, dated November 27, 1877; but we do not confine ourselves to this application of our novel combinations of parts, as hereinafter claimed.

Referring to the drawings, A represents the lay-race, and B the breast-beam of the loom.

C represents the shipper-rod, mounted in pivotal bearings immediately below the breast-beam, which carries at one end the shipper-handle of said Knowles belt-shipper, said rod for the purpose of the present invention being provided with a short crank-arm c, 75 adjustable angularly upon the rod and fastened by a screw c².

D represents a trip-lever turning on a horizontal pivot-bolt d and having an upwardly-projecting effective end, which projects adjacent to the lay in the retracted position of the latter.

E represents a bracket rigidly attached to the back of the breast-beam by bolts e, and provided at said bolts with vertical slots e², 85 for example, whereby it is rendered vertically adjustable for so adjusting said lever D, and at said pivot-bolt d with a horizontal slot e³, for example, as means for adjusting said lever D as to its distance behind the cloth-beam, 90 and F represents a connecting-rod coupled by pivot-bolts f f² to said crank-arm c of the rod C and to the lower end of said lever D, respectively, and adjustable by a series of holes d² in the lever D, for example, to reduce or increase the extent of the transmitted motion.

G represents a warp-supporting guard, and H a housing below such guard attached to the front of the lay-race A, the housing H having at the bottom a projection h, provided 100

with a horizontal pivot p . I represents a "whop-over," turning on said pivot p and constituting a "lifter," as it has been and is hereinafter termed, having an axial bore i , 5 Fig. 7, fitted to said pivot and a lifting-lug i^2 on its exposed side to transmit motion therefrom. J represents a vertically-sliding lifter-rod having its guides in said housing H and provided near its lower end with a laterally-projecting stud-arm j , which is engaged by 10 said lug i^2 and is conveniently rendered adjustable as to height by an attaching-screw s , for example; and K represents a weft-feeling fork, which is pivoted within the upper end 15 of said housing H by a horizontal pin p^2 and composed of a pair of renewable feelers k , of wire, a screw-fastened cap or keeper k^2 , by which the feelers are rigidly held in place, and a peripherally-toothed hub k^3 , provided 20 also with a drilled and tapped lug k^4 , to which a stop-screw s^2 is fitted, so as to limit the elevation of the feelers by the lifter I through the lifter-rod J, the upper end of this rod being provided with rack-teeth j^2 in mesh with 25 the pinion-teeth on said hub k^3 . (See Fig. 3.)

L represents the customary feeler-groove in the top of the lay-race, and b a central bridge of wire within the same to afford an intermediate support for the filling-thread crossing it.

30 M represents a self-adjusting spring-finger attached at its front end to the bottom of the breast-beam and projecting rearwardly immediately above the plane of the lifter I, upon 35 which it presses downwardly.

n n^2 represent oppositely-beveled notches in the bottom of the finger M.

a represents the apex of the lifter I, which is engaged by said notches n n^2 in alternate 40 succession as the lifter moves back and forth with the lay, so as to turn the lifter first in one direction and then in the other for the performance of its functions, and n^3 represents a readjusting-notch in said finger M, 45 beveled like said notch n^2 , but located nearer the breast-beam than said notch n . During each retreat of the lay said apex a of the lifter I is engaged by said notch n , and the lifter is thus turned by the spring-finger M, so as to 50 bring its lug i^2 into contact with said stud-arm j and thereby elevate the lifter-rod J, and by the coaction of said rack-teeth j^2 and toothed hub k^3 to turn the fork K, so as to elevate its feelers k . The parts are shown 55 in this position in Fig. 1 and in full lines in Fig. 2. The shuttle, if it be present, then passes freely under or behind the feelers, and the filling-thread, if all right, is stretched across the feeler-groove L and bridge b in the 60 path of the feelers.

Near the beginning of each forward movement of the lay (illustrated, as aforesaid, by Fig. 2 and represented by the arrow x in this figure) said apex a of the lifter I engages 65 with said notch n^2 of the spring-finger M and the lifter is turned into its reversed position, as shown in dotted lines in Fig. 2 and in full

lines in Fig. 3, gradually withdrawing the long bearing-surface of said lug i^2 from contact with said stud-arm j as the released lifter-rod J and feelers k gravitate. If the feelers are intercepted by the filling-thread, the lifter-rod J can only partially descend and remains wholly above the plane of the trip-lever D. Consequently, when the filling-thread is 70 all right, the lower end of the rod J passes freely above and clear of the upper extremity of the trip-lever D, and the belt-shipper is undisturbed. When the filling-thread is absent, as in the drawings, the feelers k descend to 75 the bottom of the feeler-groove L, and there is consequently a full movement of the fork K, the lifter-rod J is fully lowered, and when the downwardly-projecting lower end of the lifter-rod reaches the upper end of the trip-lever D in its path the two meet, the lever, 80 turning freely on its pivot, is shifted, as represented in dotted lines in Fig. 2, and its motion is transmitted by the connecting-rod F and crank-arm c to the rod C, turning the 85 latter in its bearings and thereby actuating the belt-shipper, all of which is thus readily accomplished before the reed strikes the lay of the cloth, as aforesaid.

The lay attachments are shown in Fig. 3 in 95 full lines as they appear in the forward position of the lay, whether the loom be running or stopped. After drawing the lay to this position if need be after it is stopped, the lay is pushed back by hand, as represented by the arrow y, Fig. 3, and during this movement of the lay the apex a of the lifter I is engaged by the notch n of the finger M, and the lifter is thus turned so as to elevate the lifter-rod J and feelers k , as during each retreat of the 100 lay when the loom is running. In case the weaver, in so moving the lay by hand when the crank is on the bottom center, should push the lay back less than the extreme distance, so that the apex of the lifter I would not pass the notch n^2 , then starting the loom would bring the lay forward to the fell of the cloth again, as represented by the arrow z, Fig. 3, with the feelers still lifted and the lifter in the position in which it is shown in dotted 105 lines in Fig. 3, and if it were not for said readjusting-notch n^3 the feelers would not be lowered until the next succeeding pick. Provided with said notch n^3 the finger M at once 110 reverses the lifter and lowers the feelers, so that the lifter-apex a coacts with the notch n , as above, during the immediately ensuing retreat of the lay.

Details which have not been specified may be of any approved description, and modifications such as will be required in adapting the stop-motion to other makes of looms will suggest themselves to machinists accustomed to building looms and loom attachments.

Having thus described our said stop-motion, 115 we claim as our invention and desire to patent under this specification—

1. In combination with the feelers and connections, a whop-over lifter carried by the lay

and a relatively stationary finger having beveled notches to engage with the apex of the lifter for turning said lifter to raise and lower said feelers, substantially as hereinbefore specified.

5. 2. In combination with the whop-over lifter, lifter-rod, feelers, and connections, a self-adjusting spring-finger pressing upon the lifter and provided with beveled notches to engage 10 with the apex of the lifter for turning said lifter to raise and lower said feelers, substantially as hereinbefore specified.

15 3. In combination with the whop-over lifter, lifter-rod, feelers, and connections, a relatively stationary finger having beveled notches to engage with the apex of the lifter during each advance and retreat of the lay and provided with a supplemental feeler lowering or readjusting notch immediately behind the 20 breast-beam, substantially as hereinbefore specified.

4. The combination, with the weft-feeling fork and the vertically-sliding lifter-rod, of a trip-lever turning on a horizontal pivot and adjustable as to its distance behind the breast-beam, a vertically-adjustable bracket to which said lever is so pivoted, adjustable connections comprising a connecting-rod coupled to the lower end of said trip-lever, and a crank-arm angularly adjustable upon the customary stop-rod below the breast-beam and to which the other end of said connecting-rod is coupled, the upper end of said trip-lever projecting normally in the path of the fully-lowered lifter-rod at a point adjacent to the lay 30 in its retracted position, substantially as hereinbefore specified.

GILBERT PARK.
JOHN E. GODDARD.
